UNITED STATES PATENT OFFICE

EDWARD J. GROSS, OF NEW ROCHELLE, NEW YORK

DESIGN FOR A JEWELRY BOX OR ARTICLE OF SIMILAR NATURE

Application filed January 20, 1931. Serial No. 38,388. Term of patent 3½ years.

To all whom it may concern:

Be it known that I, EDWARD J. GROSS, a citizen of the United States, residing at New Rochelle, in the county of Westchester and State of New York, have invented a new, original, and ornamental Design for a Jewelry Box or Article of Similar Nature, of which the following is a specification, reference being had to the accompanying drawings, forming a part thereof.

Fig. 1 is a perspective view of a jewelry box in closed position, showing my new design.

Fig. 2 is a front elevational view thereof.
Fig. 3 is a perspective view thereof in open position.

Fig. 4 is a rear elevational view thereof.
The drawing is lined to indicate the colors red and black.

I claim:

The ornamental design for a jewelry box or article of similar nature as shown and described.

In testimony whereof I affix my signature.

EDWARD J. GROSS.
